PORTABLE TAPE RECORDER

Walter E. Willday, Leeds, England, assignor to E. I.
Arnold & Son Limited, Leeds, England, a corporation
of Great Britain

Filed June 18, 1969, Ser. No. 17,750
Claims priority, application Great Britain Apr. 16, 1969

Term of patent 7 years

Int. Cl. D14—01, 03

U.S. Cl. D26—14

FIG. 1

FIG. 2

FIG. 3

FIG. 4

FIG. 5

FIG. 6

FIG. 1 is a perspective view of the portable tape recorder;

FIG. 2 is a rear view of FIG. 1;

FIG. 3 is a front view of the tape recorder;

FIG. 4 is a top plan of the portable tape recorder;

FIG. 5 is a side view of the portable tape recorder; and

FIG. 6 is a view of the other side of the portable tape recorder.

The side shown in FIG. 5 is a view looking on the right of FIG. 3 and the side shown in FIG. 6 is a view looking on the left of FIG. 3.

I claim:

The ornamental design for a portable tape recorder, as shown and described.
